(57) **CLAIM**

The ornamental design for a powder press, as shown and described.

DESCRIPTION

FIG. 1 is a top perspective view of a powder press, showing my new design;

FIG. 2 is a bottom perspective view thereof;

FIG. 3 is a front elevation view thereof, the rear elevation, the left side elevation view and the right side elevation view are identical;

FIG. 4 is a top plan view thereof;

FIG. 5 is a bottom plan view thereof; and,

FIG. 6 is a cross-sectional view along section line 6-6 of FIG. 3.

The broken lines in the figures are for the purposes of illustrating portions of the powder press, which form no part of the claimed design.

1 Claim, 6 Drawing Sheets
